GLASS DRAWING TANK

Walter O. Amsler, Butler, Pa., assignor to Frazier-Simplex, Inc., a corporation of Delaware

Application March 29, 1937, Serial No. 133,523

4 Claims. (Cl. 49—17)

This invention relates to tanks for the drawing of glass in sheet form, and consists in a feature of structure that permits the doing away with an otherwise indispensable adjunct; and, in consequence, the structure as a whole is simplified, operation is expedited, and a source of defect is eliminated.

In the accompanying drawing Fig. I is a fragmentary view in vertical section of a tank of my invention, showing the glass-drawing operation in progress; Fig. II is a view in vertical section, on the plane indicated at II—II, Fig. I; and Fig. III is a view corresponding to Fig. I of a tank in which the feature that constitutes the invention is present in modified form.

Referring, first, to Figs. I and II, the drawing chamber of the glass-drawing tank of the invention is indicated at 1. The chamber will be understood to be continuous with a melting chamber, not shown, but lying to the right of the drawing chamber, as viewed in Fig. I. The tank will be seen to be free and unobstructed, so that circulation currents, indicated by arrows, have free course.

The drawing chamber is roofed over, as indicated at 2, and through the roof a drawing opening 3 is formed. From the roof curtain walls 4 depend, screening the path of the sheet as it rises from the surface of the pool G of molten glass within the tank upward through the drawing opening 3. Beneath the roof and beyond the curtain walls 4 means may be provided for maintaining proper conditions of temperature for drawing. Such temperature-maintaining means so disposed are known, and, since they form no part of this invention, they are not shown.

Through the opening 3 in the roof of the drawing tank the sheet of glass S is drawn directly from the free surface of the molten pool G. With the exception hereinafter to be described, the structure and the accessory appliances incident to the drawing of the sheet are circumstantial to this invention. Such details of structure and of accessory appliances are shown, merely by way of example of an operative whole. To these particular details the invention is not limited. The glass is engaged primarily by a bait (not shown). As the sheet S rises its edges are first engaged by pairs of knurled rolls 5. It then passes between coolers 6, and thence upward through the opening 3 and into an annealing chamber 7, where it is engaged by pairs of drawing and guiding rolls 8. These details of drawing apparatus are more fully described in Letters

Patent No. 2,057,357, granted, on my application, October 13, 1936.

In the operation of glass-drawing apparatus such as that typically described, the glass rises in meniscus shape from the molten mass of the pool and at the base of the up-drawn sheet; and, in consequence of the variability of conditions that cannot be perfectly controlled, that rising meniscus tends to shift beneath the drawing means, this way and that, with a consequent unevenness in the thickness of the developed sheet. Means are known to reduce this tendency to shift and to give greater definiteness of place to the meniscus. Such means are typically found in a bar of solid and refractory material, submerged just below the surface of the pool of molten glass and extending in the plane of and directly beneath the path in which the drawn sheet rises. See, for example, Letters Patent 1,339,229, granted, on the application of Harry G. Slingluff, May 4, 1920. Such bar, cooling the molten glass as it approaches the region of the meniscus, has the effect of diminishing the fluctuation of position that has been indicated, and of improving the uniformity of the drawn sheet.

There are inevitable disadvantages consequent on the presence of such a bar at the place indicated. It is subject to the action of the molten glass streaming over its surfaces. There is no available material that under such conditions will not wear away. The bar, therefore, must periodically be replaced and renewed. The bar, having thus to be renewed, becomes itself an appreciable item of added expense of installation. More important by far is the delay of operation incident to replacement. And, besides, particles of the substance of the bar, so eroded away, enter into the body of glass as the sheet forms and become blemishes in the drawn sheet.

This invention consists in the discovery that, by modification in the structure of the walls of the drawing tank itself, the desired effect of stabilizing the meniscus at the base of the developing sheet may be gained, and such an accessory bar as has been indicated may be eliminated, and its undesired incidental bad effects avoided.

The bottom and side walls of the drawing tank include layers of material of high heat-insulating value. In the drawing, such a layer is indicated at 9. This material is relatively costly, and, so far as concerns strength and refractoriness, other material is more suitable. Accordingly, it is usual to make these tank walls compound, and to include in their structure an inner layer 10 of

refractory tank block, and an enveloping layer 9 of more highly heat-insulating character. I have found (and herein lies my invention) that by reducing the degree of heat insulation and 5 increasing the degree of heat conductivity of the wall of the drawing chamber in the region immediately beneath and in substantially the plane of the developing sheet, the desired effect will be gained: the glass, elsewhere of the highly molten 10 condition desired, becomes cooler as it approaches the meniscus at the base of the developing sheet; and the meniscus gains stability.

In Figs. I and II I have shown a drawing chamber whose bottom wall extends in uniform 15 horizontal plane, and whose side walls rise vertically beyond the limits of the breadth of the updrawn sheet. From the bottom and side walls the insulating layer 9 is absent throughout a narrow and sufficient interval 11; the insulating 20 envelope is discontinuous in an interval that coincides with and extends substantially in the plane of the up-drawn sheet. It suffices that this slot extend, as shown in Fig. I, upward in the side walls, from the bottom toward, but to a 25 limit preferably lower than, the normal level of the pool of molten glass within the tank.

In consequence of such refinement of tank-wall structure, the meniscus at the base of the developing sheet will be found to be stabilized, and 30 the quality of the sheet such as is desired.

In Fig. III I have shown the bottom wall of the drawing chamber of the tank to be stepped; the riser 12 of this step to be left, free of a covering of insulation; and the vertical extent of the 35 riser to be sufficient, that it is exposed over an outer uninsulated area to the cooling effect of the air. This step in the bottom of the tank is not an obstruction to the free circulation of the molten glass; to the contrary, its relatively cool 40 riser has effect to accelerate the descending current adjacent its surface. This step is so situated that the portion of the body of glass that is subject to its cooling effect is precisely the portion that is disposed beneath and in substantially the 45 plane of the up-drawn sheet. It has, however, the effect that the meniscus at the base of the up-drawn sheet is stabilized, and the sheet is of desired quality.

I claim as my invention:

50 1. In apparatus for the drawing of glass in sheet form, the combination of a tank free of interior obstruction to circulation, and means for drawing a sheet of glass vertically upward in a

plane of determined position from the free surface of a pool of molten glass within the tank, the tank walls of heat-insulating character, exposed externally to the cooling effect of the atmosphere, being of diminished insulating effect 5 in the region beneath and substantially in the sheet-developing plane of the aforesaid drawing means, whereby the body of glass within the tank in the region of such plane is cooled and the meniscus that forms at the base of the developing sheet is stabilized in position. 10

2. In apparatus for the drawing of glass in sheet form, the combination of a tank free of interior obstruction to circulation, and means for drawing a sheet of glass vertically upward in a 15 plane of determined position from the free surface of a pool of molten glass within the tank, the tank walls, exposed externally to the cooling effect of the atmosphere, including in their structure a layer of heat-insulating material, the continuity of such layer being interrupted in the 20 region beneath and substantially in the sheet-developing plane of the aforesaid drawing means.

3. In apparatus for the drawing of glass in sheet form, the combination of a tank free of 25 interior obstruction to circulation, and means for drawing a sheet of glass vertically upward in a plane of determined position from the free surface of a pool of molten glass within the tank, the bottom wall of the tank being formed with 30 a step including a riser that extends in vertical plane adjacent the sheet-developing plane of the aforesaid drawing means, the tank walls of heat-insulating character, exposed externally to the cooling effect of the atmosphere, being of diminished insulating effect within the extent of 35 said riser, whereby the molten glass within the tank is chilled in the plane of the up-drawn sheet and the meniscus that is formed at the base of the up-drawn sheet is stabilized in position. 40

4. A tank for the drawing of glass in sheet form having a roof provided with a transverse slot through which the sheet is drawn, and having walls of heat-insulating character exposed externally to the cooling effect of the atmosphere, 45 the said walls immediately beneath and substantially in the plane of the said slot in the roof being of diminished heat-insulating effect, whereby, in operation, the meniscus that forms at the base of the developing sheet is stabilized in 50 position.
